UNITED STATES PATENT OFFICE.

DAVID McNEILL, OF WADE, NORTH CAROLINA.

DESIGN FOR A COMBINED TOBACCO-PLUG REMOVER AND BOX-OPENER.

48,731.

Specification for Design.

Patented Mar. 14, 1916.

Application filed July 22, 1915. Serial No. 41,412. Term of patent 14 years.

To all whom it may concern:

Be it known that I, DAVID McNEILL, a citizen of the United States, residing at Wade, in the county of Cumberland and State of North Carolina, have invented a new, original, and ornamental Design for a Combined Tobacco-Plug Remover and Box-Opener, of which the following is a specification, reference being had to the accompanying drawing, forming part thereof, in which—

Figure 1 is a plan view, and Fig. 2 is a side view of the device exhibiting the design.

I claim:

The ornamental design for a combined tobacco-plug remover and box-opener, as shown.

DAVID McNEILL.
